UNITED STATES PATENT OFFICE.

PASQUALE BUFFARDI, OF IRVINGTON, NEW JERSEY, ASSIGNOR TO EDMUND W. ZEH,
OF NEWARK, NEW JERSEY.

ADJUSTABLE ECCENTRIC.

Application filed September 24, 1924. Serial No. 739,504.

The invention relates in general to eccentrics which are adjustable to vary the eccentricity for different purposes, for instance, to adjust the stroke of the pitman or connecting rod of a press or other machine in which power or motion is transmitted or applied through a rotating shaft and pitman.

The objects of the invention are to provide an adjustable eccentric which can be used between spaced journals of a shaft without dividing said shaft transversely into separable sections; to enable such a shaft to be continuous or in one integral piece throughout said bearings and the space between them; to thus retain unimpaired the strength and durability of the shaft; to secure novel and improved features of construction of an adjustable eccentric which will enable it to be used on such a shaft; to arrange the adjustable parts outside the periphery of the shaft; to provide the shaft with an eccentric portion whose circumferential surface lies wholly outside the periphery of the shaft; to secure a construction which can be easily and quickly adjusted and in which the parts are positively held against working or wearing loose from adjusted relations, and to obtain other results and advantages as may be brought out by the following description.

For the purpose of illustrating and describing the principles of my invention and a preferred embodiment thereof, I have shown in the accompanying drawings the invention applied to a power press to adjust the stroke of the pitman actuating a reciprocating die, but it should be understood that the invention is susceptible of other uses without departing from its spirit or scope.

Referring to said drawings in which the same characters of reference designate corresponding and like parts throughout the several views,

Figure 1 is a front elevation of a power press having an eccentric constructed in accordance with the invention;

Figure 2 is an enlarged vertical longitudinal sectional view through the eccentric;

Figure 3 is a transverse vertical sectional view taken on the line 3—3 of Figure 2;

Figure 4 is a transverse vertical sectional view taken on the line 4—4 of Figure 2;

Figure 5 is a transverse vertical sectional view taken on the line 5—5 of Figure 2;

Figure 6 is an end elevation of the shaft and the notched flange to hold the eccentric bushing against rotation, and

Figure 7 is a detached end elevation of the eccentric bushing.

Specifically describing the present embodiment of the invention the reference character A designates the frame of a power press upon which is journaled a drive shaft B carrying a drive pulley or wheel C, said shaft being connected through the eccentric D embodying the invention and the pitman E to a die carrying block, hammer or the like F, whereby rotation of the shaft B causes reciprocation of the block F.

The shaft B is formed intermediate its ends with an integral eccentric portion 1 forming a crank, and an annular flange 2 at one end of said crank, which crank forms a body for the adjustable eccentric. The crank 1 tapers or gradually decreases in diameter from said flange toward the other end which is screw-threaded at 3 to receive a nut or collar 4; and all points on the periphery of said crank are outside the peripheries of the ends of the shaft to permit the nut 4 to be slipped on from the end of the shaft.

An eccentric bushing or sleeve 5 is mounted and capable of rotation and longitudinal movement upon said crank or body 1 between the flange 2 and the nut 4, the inner walls of said bushing being tapered to fit the crank while the outer walls are substantially cylindrical. The eccentricity of the bushing 5 is complementary to that of the crank 1 so that by rotating the bushing on the crank, the eccentricity of the bushing to the shaft B may be varied or adjusted.

For holding the bushing 5 in adjusted position on the crank 1, the flange 2 is formed with a plurality of circumferentially spaced notches 6, and the end of the bushing 5 adjacent said flange is provided with a lug or projection 7 to fit any of said notches. With said lug arranged in either of said notches, the bushing will be held against rotation on the crank 1, and to hold the lug 7 in the notch, the nut 4 is screwed tight against the bushing, longitudinal movement of the bushing being thereby prevented. In making and assembling the parts, a clear-

- ance is provided between the end of the bushing 5 and the flange 2 so that tightening of the nut 4 causes the tapered interior of the bushing to ride tightly into engagement with the tapered surface of the crank, whereby lost motion or relative movement of the bushing and the crank is prevented and the bushing and the crank operate substantially as integral parts.
- 10 Where the invention is to be utilized in a press or the like as herein illustrated, the pitman E is provided with an eccentric strap G of the usual type, including the removable cap H, said strap being applied to the eccentric bushing 5 in the usual manner of application of a strap to an ordinary eccentric. With such a construction, it will be obvious that rotation of the eccentric bushing 5 on the crank 1 will vary the working length 15 and thereby the stroke of the pitman E. In other instances of use, an eccentric embodying the invention may serve the function of changing the time or relation of the stroke to other parts of a machine, movement of the bushing 5 in one direction advancing the stroke and in the other direction retarding the stroke.

To facilitate in adjusting the bushing 5 on the crank to vary the eccentricity, the 20 end of the bushing adjacent the nut 4 is provided with recesses 8 to receive a turning tool or implement. In adjusting the eccentric, the nut 4 is first loosened and the bushing 5 pushed longitudinally to remove the lug 7 from the notch 6. This action forces the other end of the bushing outwardly from beneath the eccentric strap G sufficiently to expose the recesses 8 so that a suitable tool or implement, such as a metal rod, may be 25 inserted into one of the recesses, or successively into each, to turn the bushing on the crank to the desired position. With such a construction, it is unnecessary to entirely disconnect the parts of the eccentric 30 from each other or the eccentric strap from the eccentric, and the operation of adjusting the eccentric is extremely simple.

It is to be noted that the eccentric embodying my invention consists of a small number 35 of simple and comparatively inexpensive parts, which ensure strength and durability. Further, the invention avoids the necessity for forming the drive shaft in two parts as is common in some devices of this character, and due to the particular construction and arrangement of the parts there is a minimum 40 tendency for the parts to work out of adjusted relation or to unduly wear.

Obviously various modifications may be 45 made by those skilled in the art in carrying out my invention, without departing from the spirit and scope thereof, and I do not desire to be understood as limiting myself except as required by the following claims

when construed in the light of the prior 65 art.

Having thus described the invention, what I claim is:—

1. A shaft having spaced journals and an eccentric portion between said journals, a 70 pitman on said eccentric portion, an eccentric bushing between said eccentric portion and pitman and capable of movement both longitudinally and rotatably with respect to said parts, cooperating means at one end 75 of said eccentric portion and on said bushing adapted to engage and disengage upon longitudinal movement of said bushing in opposite directions to hold and release said bushing respectively against and for rotation on said eccentric portion, and means at the other end of the eccentric portion for releasably holding the bushing against longitudinal disengagement of the said cooperating means at the first-mentioned end 80 of the eccentric portion and bushing.

2. A drive shaft for presses or the like having a crank intermediate its ends, a bushing eccentrically mounted and capable of longitudinal and rotative movement on 90 said crank, cooperating means at one end 95 of said crank and on said bushing adapted to engage and disengage upon longitudinal movement of said bushing in opposite directions to hold and release said bushing respectively against and for rotation on said crank, the other end of said crank being threaded, and a nut upon said threaded end of the crank to engage the adjacent end of 100 said bushing and influence the bushing toward the other end of the crank.

3. A drive shaft for presses or the like having an enlarged portion intermediate its ends eccentric with respect to the axis of the shaft, all points on the periphery of 105 said eccentric portion being outside the peripheries of the ends of the shaft, said eccentric portion being threaded at one end and having an annular flange at the other end formed with circumferentially spaced recesses, a nut on said threaded end, and a bushing eccentrically mounted and capable 110 of longitudinal and rotative movement on said eccentric portion, the end of said bushing adjacent said flange having a lug to engage any of said recesses in said flange upon longitudinal movement of said bushing toward said flange to hold said bushing against rotation.

4. A shaft having spaced journals and an eccentric portion between said journals tapered for part of its length, a pitman on 120 said eccentric portion, an eccentric bushing between said eccentric portion and pitman and interiorly tapered to fit the said tapered part of the former, cooperating means on 125 said eccentric portion and said bushing adapted to engage and disengage upon lon-

itudinal movement of said bushing in opposite directions to hold and release said bushing respectively against and for rotation on said eccentric portion, and means on the untapered part of the eccentric portion for engaging the adjacent end of the bushing and forcing it onto the tapered part.

5. A shaft having spaced journals and an eccentric portion between said journals 10 tapered for part of its length, a pitman on said eccentric portion, an eccentric bushing between said eccentric portion and pitman and interiorly tapered to fit the said

tapered part of the former, cooperating means on said eccentric portion and said bushing adapted to engage and disengage upon longitudinal movement of said bushing in opposite directions to hold and release said bushing respectively against and for rotation on said eccentric portion, and 15 a nut on the untapered part of the eccentric portion for engaging the adjacent end of the bushing and forcing it onto the tapered part. 20

PASQUALE BUFFARDI.
